UNITED STATES PATENT OFFICE.

CLARENCE C. BERRY, OF VALLEY PARK, MISSOURI.

AIRSHIP.

1,343,428.

Specification of Letters Patent. Patented June 15, 1920.

Application filed June 6, 1919. Serial No. 302,241.

To all whom it may concern:

Be it known that I, CLARENCE C. BERRY, a citizen of the United States, residing at Valley Park, Missouri, have invented a 5 certain new and useful Improvement in Airships, of which the following is a full, clear, and exact description, such as will enable others skilled in the art to which it appertains to make and use the same, reference being had to the accompanying drawings, forming part of this specification.

My invention relates generally to the art of aerial navigation and more particularly to a new and novel form of dirigible airship, the principal object of my invention being to generally improve upon and simplify the construction of the existing types of airships.

A further object of my invention is to 20 provide an airship having a pair of elongated cylindrical bodies arranged substantially parallel with each other, each body being adapted to receive a plurality of buoyant gas bags or like containers, and to 25 arrange between said bodies an elongated cabin structure which co-operates with the cylindrical bodies in forming a sustaining plane which is effective in materially increasing the lifting and carrying capacity 30 of the airship.

A further object of my invention is to provide an airship embodying some of the desirable characteristics of a marine catamaran, in order to materially increase the 35 stability of the airship during flight and at the same time minimizing resistance to the air, and further, to arrange the driving propellers upon the medial line of air resistance, thereby producing maximum propelling effect and enabling the airship to 40 be driven forwardly at a relatively high speed.

A further object of my invention is to construct and form the end portions of the 45 twin bodies of the airship so as to minimize the disturbance of atmosphere during the forward flight of the machine, thereby decreasing head resistance and likewise materially decreasing the so-called back-wash or 50 frictional contact of the air with the surfaces of the ship's body during forward movement thereof.

A still further object of my invention is to provide for the positive control of an 55 airship, thereby enabling the ship to be operated in practically all weather conditions,

and further, to provide an airship that is capable of carrying comparatively heavy loads.

With the foregoing and other objects in 60 view, my invention consists in certain novel features of construction and arrangement of parts, hereinafter more fully described and claimed, and illustrated in the accompanying drawings, in which—

Figure 1 is a side elevational view of an airship of my improved construction.

Fig. 2 is a top plan view of the airship.

Fig. 3 is a front elevational view of an airship of my improved construction.

Fig. 4 is a cross sectional view showing the construction of the framework for the twin bodies of the airship and the framework for the centrally disposed cabin structure.

Fig. 5 is a cross sectional view taken approximately on the line 5—5 of Fig. 2.

Referring in detail to the accompanying drawings which illustrate a practical embodiment of my invention, it will be seen 80 that my improved airship includes a pair of elongated cylindrical bodies 10 of uniform size and construction, said bodies being arranged parallel with each other and spaced apart a suitable distance. Each of these 85 bodies is made up of a suitable framework which includes longitudinally disposed ribs 11 and transversely disposed frames which are composed of a plurality of truss structures 12 and the corresponding transverse 90 framework of one body is connected to the corresponding framework of the other body by suitable connecting rods and braces 13.

The framework of each elongated cylindrical body thus constructed is covered with 95 suitable material, preferably water-proof fabric, although said covering may take the form of thin metal plates, wood, fiber, or the like, and the chambers within each body between the transverse frames are adapted to receive inflatable bags or containers (not shown) for hydrogen or other buoyant gas.

Arranged between the elongated cylindrical bodies and preferably disposed below the horizontal center line thereof is a framework 14 which is wholly or partially enclosed to form an elongated cabin 15. This cabin is of sufficient size to contain the driving motors and operating mechanism for the airship and may be also fitted for the 105 accommodation of passengers and freight.

Suitable propellers 16 are mounted for op-

eration at both ends of the cabin structure, said propellers being driven in any suitable manner, preferably by internal combustion engines, and if desired, propellers may be 5 located at various points along the cabin structure, as shown by dotted lines in Fig. 1.

The elongated cabin disposed between the cylindrical bodies 10 provides a structure which has a considerable horizontal surface 10 and therefore the complete structure has the general form of a relatively large elongated plane which, when driven forwardly by the propellers, exerts great lifting and sustaining powers and at the same time 15 giving a relatively high degree of stability in the presence of wind or adverse air currents.

The inner faces of the end portions of each elongated body are curved gradually 20 outward until they meet the outer peripheral portions of said bodies, thereby providing substantially straight vertical faces 17 which are curved lengthwise and extend from the extreme terminal portions of the 25 bodies 10 to points on the inner sides of the bodies adjacent to the ends of the cabin structure 15. This construction is effective in materially reducing air resistance against the forward end of the flying machine during 30 its forward movement for during such movement the air striking against the curved faces 17 will be forced toward a medial line between the bodies 10 and will pass rearwardly between said bodies immediately 35 above and below the cabin structure, and which action tends to increase stability and maintain the equilibrium of the machine during flight. Further, as the air is deflected inwardly in both directions by the 40 curved faces 17 at the forward ends of the bodies, said air will to a certain extent be compressed and in such condition will be engaged by the forward propellers with the result that the latter are much more efficient 45 than where they are operating in normal atmosphere. Further, the drawing-in of the air between the forward ends of the cylindrical bodies to a certain extent forms a partial vacuum immediately in front of 50 the machine, and such action materially decreases head resistance during flight.

Arranged on the outer sides of the bodies 10 near their rear ends are horizontally disposed planes 18 which are provided with 55 suitable operating mechanism, and said planes being mounted to rock upon horizontal axes in order that they may perform the functions of elevating planes to guide the machine vertically during its forward 60 flight.

Disposed at the rear ends of the bodies 10 and operating upon vertical axes are 65 rudders 19 which are preferably connected so as to operate in unison and these rudders are utilized for steering the machine later-

ally in either direction during forward flight.

It will be readily understood that minor changes in the size, form and construction of the various parts of my improved airship 70 can be made and substituted for those herein shown and described, without departing from the spirit of my invention, the scope of which is set forth in the appended claims.

What I claim is:

1. In an airship of the class described, a pair of connected elongated cylindrical bodies arranged substantially parallel with each other, the forward ends of which bodies are provided with vertically disposed longitudinally curved faces which extend from the inner sides of the bodies forwardly to the outer sides of said bodies. 75

2. In an airship of the class described, a pair of connected elongated cylindrical bodies arranged substantially parallel with each other, the forward ends of which are provided with vertically disposed faces which gradually curve outwardly away from each other and terminate at the outer sides 90 of said bodies. 85

3. In an airship of the class described, a pair of connected elongated cylindrical bodies, the forward ends of which are provided with faces which are inclined with respect to the axes of said bodies, and said faces extending from the inner sides of the body forwardly to the outer sides thereof. 95

4. In an airship of the class described, a pair of connected elongated cylindrical bodies, the forward ends of which are provided with faces which are inclined with respect to the axes of said bodies, said faces extending from the inner sides of the body forwardly to the outer sides thereof, and 100 a cabin structure disposed between said bodies. 105

5. In an airship of the class described, a pair of elongated cylindrical bodies, the ends of which are provided with vertically 110 disposed longitudinally curved faces which extend from the inner sides of the bodies, forwardly to the outer sides of said bodies, and a cabin structure arranged between and connecting said bodies. 115

6. In an airship of the class described, a pair of connected elongated cylindrical bodies, the rear ends of which are provided with vertically disposed longitudinally curved faces which extend from the inner 120 sides of the bodies rearwardly to the outer sides of said bodies.

7. In an airship of the class described, a pair of elongated cylindrical bodies arranged substantially parallel with each 125 other, the forward ends of which are provided with vertically disposed faces which gradually curve outwardly away from each other from the inner sides of the bodies to the outer sides thereof, a cabin structure ar- 130

ranged between and connecting said bodies, and horizontally disposed planes arranged on the outer sides of said elongated bodies.

8. In an airship of the class described, 5 a pair of elongated cylindrical bodies arranged substantially parallel with each other, the forward ends of which are provided with vertically disposed faces which gradually curve outwardly away from each 10 other from the inner sides of the bodies to the outer sides thereof, a cabin structure arranged between and connecting said bodies, and vertically disposed rudders arranged at the rear ends of said cylindrical bodies.

9. In an airship of the class described, 15 a pair of connected elongated cylindrical bodies arranged substantially parallel with each other, the greater portion of each body

having the same diameter throughout its 20 length and the end portions of each body being provided with vertically disposed longitudinally curved faces which extend from the inner side of the body to the outer side thereof.

10. In an airship of the class described, 25 a pair of connected elongated cylindrical bodies arranged substantially parallel with each other, the greater portion of each body having the same diameter throughout its 30 length and the rear end portion of each body being provided with a vertically disposed longitudinally curved face which extends from the inner side of the body to the outer side thereof.

In testimony whereof I hereunto affix my signature this 3d day of June, 1919.

CLARENCE C. BERRY.
